PATENTED APR 5 1870

United States Patent Office.

CHARLES CONDON, OF ROCHESTER, NEW YORK.

Design No. 3,950, dated April 5, 1870.

DESIGN FOR PRUNING-SHEARS.

The Schedule referred to in these Letters Patent and making part of the same.

I, CHARLES CONDON, of the city of Rochester, in the county of Monroe and State of New York, have invented and produced a new and original design for Pruning-Shears and Hatchet, of which the following is a specification.

The nature of my design consists in the V-shape of the knife-edge and the corresponding shape of the hook, and also in the hatchet-blade formed on the back of the hook, substantially as hereinafter set forth and represented.

The drawing represents a side view of my new design.

In the drawing—

A indicates the knife-blade with its cutting-edge c made of the V-form represented; and

B is the hook, which is of a corresponding shape to that of the edge of the knife or cutter.

The knife A and hook B are jointed together at a by means of a bolt, and are provided with shanks or extensions b b that are secured in the ends of the handles D D, which may be of any desired length.

The back of the hook B is formed with a hatchet-blade or cutter e, for clipping off the twigs and small branches.

The ferrule d on the end of one of the handles is provided with lips or flanges f f, between which the rubber-block g is secured, to prevent the handles from closing too far, so as to protect the fingers.

By my improved form of the knife-blade and of the hook, a stronger purchase is obtained and a much more effective action is afforded for the cutting parts, and, by means of the hatchet-blade e, the smaller sprouts and branches may be easily severed without the use of the shears.

If desired, the blade e may be formed on the back of the knife A, instead of the hook.

What I claim as of my invention is—

The design for pruning-shears and hatchet herein described, substantially as represented and set forth.

In testimony whereof I hereunto sign my name in the presence of two subscribing witnesses.
